F.M. MULTIPLEX STEREOPHONIC BROADCAST RECEIVER

Ryokichi Imamura, Tokyo, and Koro Suzuki, Hanno, Japan, assignors to Oki Electric Industry Company Limited, Tokyo, Japan, a corporation of Japan

Filed Oct. 17, 1963, Ser. No. 316,814

Claims priority, application Japan, Feb. 5, 1963, 38/4,595

1 Claim. (Cl. 179—15)

This invention relates to demodulators for F.M. multiplex stereophonic broadcast receivers and to stereophonic broadcast receivers.

An object of the present invention is to improve the degree of separation of signals in stereophonic broadcasts.

Another object of the present invention is to prevent the generation of beat sounds and to elevate the degree of separation of right and left sounds.

A further object of the present invention is to use an ordinary F.M. demodulating circuit instead of the demodulating circuit for stereophonic broadcasts in the case of using the stereophonic broadcast receiver for single-dimensional broadcasts.

In the accompanying drawings.

FIGURE 1 is a circuit diagram of a demodulator for a conventional F.M. receiver.

FIGURE 2 is a view showing frequency spectra of signals demodulated by the frequency discriminator in FIGURE 1.

FIGURE 3 is a circuit diagram showing an embodiment of the demodulator according to the present invention.

FIGURE 4 is a circuit diagram showing another embodiment of the demodulator according to the present invention.

FIGURE 5 is a view showing a demodulating circuit in the case of receiving single-dimensional broadcasts in a receiver for stereophonic broadcasts.

The present invention shall be detailed with reference to the accompanying drawings.

FIGURE 1 shows a demodulating circuit for a conventional F.M. multiplex stereophonic broadcast receiver. 1 is a high frequency amplifying part of the receiver. 2 is a frequency discriminator. 3 is a low-pass filter. 4 is a filter for removing contract broadcast bands. 5 is an oscillator. 6 is a multiplier. 7 is a band-pass filter. As the circuit is wired as illustrated, the oscillator 5 is synchronized by a signal of 19 kc., and higher harmonics just twice as large are formed by the multiplier 6 and are added to demodulating diodes or rectifiers 8 and 9. On the other hand, a contract broadcast frequency of 67 kc., unnecessary for F.M. stereophonic broadcasts, is removed by means of the filter 4. L+R sound parts of 19 kc. and 0-15 kc. are removed by means of the band-pass filter 7 and only a signal of 38 kc.±(L-R) is taken out and is added to the diode circuits 8 and 9 as in the diagram. However, as shown in FIGURE 2, the (L-R) signal will be in the form of modulations separated from the carrier wave of 38 kc. after the 38 kc. carrier wave has been amplitude modulated by the (L-R) signal. Therefore, when exactly the same frequency as the original 38 kc. is applied to the (L-R) signal circuit as in FIGURE 1 and is demodulated, the original low frequency signal of (L-R) will come to appear on the output side of said diodes 8 and 9. If this (L-R) signal and the (L+R) signal, which has passed through the low-pass filter 3, are combined by means of the matrix circuit illustrated, the sum and difference or the L and R signals can be derived from the terminals 18 and 19, respec-

2

tively. When they are properly amplified and are led to speakers, broadcast sounds can be heard from the right and left speakers, respectively.

In the circuit mentioned above, in case there is no L signal, if the R signal appears at the terminal 18 of the L signal, the right and left signals will not be discriminated from each other and the stereophonic broadcast will be meaningless. Therefore, the ratio of the R signal appearing at the terminal 19 to the R signal appearing at the terminal 18, in case there is no L signal, is called the degree of separation of the R signal. The smaller this value, the better.

The object of the present invention is to improve the above mentioned degree of separation. That is to say, while feeding the R signal only and measuring the R signal voltage leaking to the L signal terminal 18, the respective circuits are adjusted to minimize this value. It has been discovered that, even in case the respective circuits are reasonably adjusted so that the theoretical leakage of the R signal may be substantially zero, the leaking R signal voltage at the terminal 18 will be very large. In scrutinizing this mysterious phenomenon, it has been discovered that, when the L+R signal, coming through the low-pass filter 3 and resistors 16 and 17, and the 38 kc. output multiplier 6 are mixed together by means of the diodes 8 and 9, beat sounds will be generated and will appear at the L terminal 18. For example, in case there is no L signal but there is only the R signal as described above, if the R signal frequency coming through the low-pass filter 3 is made 6.333 kc., just six times as large as it will be 38 kc. and, when these two currents are mixed together by means of the diodes 8 and 9, the beat sounds will appear at the terminals 18 and 19. Not only will this phenomenon reduce the apparent degree of separation but also the generated beat sounds will be of a frequency quite different from the original signal and therefore, for example, in a music broadcast, a sound which is quite different from the broadcast sound will be mixed in and the tone quality of this receiver will be greatly deteriorated. In measuring commercial F.M. receivers in which the degree of separation is as low as to be, for example, about -5 to -10 db, it is found in all of them that the output of the beat has become far larger than the leakage of the substantial L or R signal. Therefore, if this beat sound is removed, the degree of separation can be remarkably improved.

The objective of the present invention is to prevent the generation of such obstructing beat sounds and to improve the degree of separation of the right and left sounds of an F.M. stereophonic broadcast receiver. For this purpose, as evident from the above described explanation, the L+R signal must be prevented from being applied to the diodes 8 and 9 without obstructing the inherent function of the demodulator. Thus, an interference preventing device comprising transistors or vacuum tubes is provided between the diode circuit, for demodulating the L-R signal of 38 kc. and taking out the L-R signal of a low frequency composition, and the matrix circuit for combining the demodulated L-R signal and the L+R signal.

An embodiment of the demodulator according to the present invention is shown in FIGURE 3. In the drawing, 20, 21, 22, and 23 are signal voltage dividers. 24 is a balancing variable resistor for matching vacuum tube characteristics. 25 and 26 are vacuum tube amplifiers. The components designated by the other numerals are exactly the same as in FIGURE 1. In this invention, the L-R signal is amplified by the vacuum tubes 25 and 26 and is fed to the matrix circuit. On the other hand, the L+R

signal is fed to the matrix circuit in exactly the same manner as in FIGURE 1. Both signals are combined in said matrix circuit. It is exactly the same as in the case of FIGURE 1 that the signals of the sum and difference or L and R signals are derived at the terminals 18 and 19, respectively. But, in FIGURE 3, as the vacuum tubes 25 and 26 are interposed between the diode circuits 8 and 9 and the $L+R$ signal input end, the $L+R$ signal will not be applied to the diode through the grids from the anodes of the vacuum tubes. That is to say, the two signals will not be mixed in the diode circuit and will not generate beat sounds as described above. On the contrary, the $L-R$ signal will appear at the anode from the grids of the vacuum tubes and will be applied to the matrix circuit. That is to say, the vacuum tubes 25 and 26 in this case can be considered to be acting as valves passing the signal from left to right in the drawing but preventing the signal from passing from right to left. Further, as the anode voltage of the vacuum tubes 25 and 26 is high enough and the anode voltage-current characteristics are linear, as different from the circuits of the diodes 8 and 9, there is no fear of generating beat sounds in this part. According to the present invention, the conventional degree of separation of about -10 db can be easily elevated to be higher than -30 db. Even if transistors are used in place of the vacuum tubes, exactly the same effect can be obtained.

In the above mentioned embodiment, by using vacuum tubes or transistors, the passage of the current in the reverse direction, and the interference of the oscillator current of 38 kc. with the $L+R$ signal, are prevented. However, such interference preventing device is not limited to vacuum tubes or transistors. In short, the device may be such as will prevent the $L+R$ signal from being applied to the diodes 8 and 9 and will effectively apply the $L-R$ signal to the matrix circuit.

In FIGURE 4 is shown another embodiment of the present invention wherein the characteristics of a rectifier of passing signals in one direction only are used for such purpose. In the drawing, the numerals 8 to 19 designate the same parts in FIGURE 1, but diodes or rectifiers 31, 32, 33 and 34 are inserted as illustrated. If the polarities of the diodes or rectifiers are connected as illustrated, the $L+R$ signal coming through the resistors 16 and 17 will be blocked by the diodes 33 and 34 and will not be applied to the diodes 8 and 9, respectively, when its phase is plus. When the phase of the $L+R$ signal is minus, the signal will pass through the diodes 33 and 34 but will be shorted by the diodes 31 and 32 and will not be applied to the diodes 8 and 9. On the contrary, the $L-R$ signal will easily pass through the diodes 33 and 34 and will not be shorted by the diodes 31 and 32.

Further, in an F.M. stereophonic broadcast receiver, by using a complicated demodulating circuit, the right and left sounds of received signals are demodulated to operate the right and left speakers, respectively. In the present invention, in the case of a single dimensional broadcast, the demodulating circuit for stereophonic broadcasts is not to be used but an ordinary F.M. demodulating circuit is to be used. The present invention provides a receiver for F.M. stereophonic broadcasts wherein a low frequency amplifying circuit is switched over by using a 19 kc. pilot signal included in F.M. stereophonic broadcasts.

According to the present invention, in view of the fact that, in the case of stereophonic broadcasts, the 19 kc. pilot signal is always being sent, by operating a relay with the energy of said signal, the demodulating circuit for stereophonic broadcasts may be automatically switched in at the time of stereophonic broadcasts, and the demodulating circuit for single-dimensional broadcasts may be automatically switched in at the time of single-dimensional broadcasts instead of stereophonic broadcasts.

In FIGURE 5, an antenna 40 is connected to a frequency discriminator 42 through a high frequency and intermediate frequency amplifier 41 of an F.M. receiver. Said discriminator 42 is connected to a demodulator 43

for F.M. stereophonic broadcasts and a de-emphasis circuit 44. Demodulator 43 has terminals *a* and *a'*, and the de-emphasis circuit 44 has terminals *b* and *b'*. Terminals *a'* and *b'* can be connected to a right signal amplifier 45 connected with a right speaker 47 through a later described contact 49. Also the above mentioned terminals *a* and *b* can be connected to a left signal amplifier 46 connected with a left speaker 48 through a later described contact 49'. The above mentioned demodulator 43 for F.M. stereophonic broadcasts is connected to a B^+ source of 150 v. through the later described contact 49''.

On the other hand, the output of the frequency discriminator 42 is connected to a series circuit of a band-pass filter 50 for 19 kc. signals, 19 kc. signal amplifier 51, rectifier 52 and relay 53. Further, a pilot lamp 54 for indicating stereophonic broadcasts and a pilot lamp 55 for indicating single-dimensional broadcasts are connected to 6 v. source through a later described contact 49''''. The above mentioned contacts 49, 49', 49'' and 49''' are operatively connected contacts for said relay 53, and will be kept in the illustrated state when said relay 53 operates.

The present invention as illustrated operates as follows. During a stereophonic broadcast, as the 19 kc. pilot signal is being sent, said signal will be taken out by the band-pass filter 50, will be amplified by the 19 kc. amplifier 51, will operate by the relay 53 by means of the rectifier 52 and will keep the contacts 49, 49', 49'' and 49''' in the illustrated positions. As a result, the output of the stereophonic broadcast will be amplified by the amplifiers 45 and 46 through the contacts *a'* and *a*. On the other hand, in case the broadcast frequency is of a single-dimensional broadcast, as there is no 19 kc. pilot signal, the relay 53 will not operate, therefore all the contacts 49, 49', 49'' and 49''' will be switched over and the broadcast frequency will be led into the amplifiers 45 and 46 through the frequency discriminator 42 and de-emphasis circuit 44 in the same manner as in an ordinary F.M. receiver. As a result, in the case of a single-dimensional broadcast, as the complicated demodulator 43 for stereophonic broadcasts is not used in the circuit formation, the tone quality will not be reduced and a favorable tone quality be enjoyed. Further, as there is a 38 kc. oscillator, having a considerably large output, for demodulating the right and left signals in the stereophonic broadcast demodulator 43, in order to prevent the generation of beat sounds by the leakage of the oscillator output, by cutting off the B^+ source with the contact 49''' in the case of a single-dimensional broadcast in which said demodulator 43 is not used, a good tone quality can be secured. Further, by simultaneously using the pilot lamps 54 and 55, whether the broadcast now coming out of the speaker is a single-dimensional broadcast or a stereophonic broadcast can be easily identified.

What is claimed is:

An F.M. multiplex stereophonic receiver for deriving left (L) and right (R) audio signals transmitted on a carrier wave as modulations of a sub-carrier in the form of sum ($L+R$) signals and difference ($L-R$) signals, said receiver comprising, in combination, a frequency discriminator; means applying the modulated carrier wave to said frequency discriminator; low pass filter means connected to the output of said frequency discriminator and passing the $L+R$ signals; band pass filter means connected to the output of said frequency discriminator and passing the $L-R$ signals; an L signal output terminal; an R signal output terminal; frequency generator means providing a sub-carrier frequency for the $L-R$ signal; combining means connected to said band pass filter means and to said generator means and mixing said sub-carrier frequency with said $L-R$ signal; means connecting the output of said low pass filter means to said output terminals to apply said $L+R$ signals to said output terminals; diode means, including plural diodes, connected to said combining means and deriving the $L-R$ signals; and rectifier means connecting said diode means to said output terminals and pro-

viding for application of said $L-R$ signals from said diode means to said output terminals while blocking application of said $L+R$ signals to said diode means; said diode means comprising a pair of first diodes each connected between said combining means and a respective output terminal; said rectifier means comprising a pair of second diodes having their anodes interconnected to ground and each having a cathode connected to a respective output terminal; said rectifier means further including a third pair of diodes each connected in a forward direction between the cathode of a respective second diode and the corresponding output terminal.
